United States Patent Office.

WILLIAM H. LEE AND CHARLES M. HARDENBERGH, OF MINNEAPOLIS,
MINNESOTA.

Letters Patent No. 79,075, dated June 23, 1868.

IMPROVEMENT IN HOT-AIR FURNACES.

The Schedule referred to in these Letters Patent and making part of the same.

TO ALL WHOM IT MAY CONCERN:

Be it known that we, WILLIAM H. LEE and CHARLES M. HARDENBERGH, of Minneapolis, in the county of Hennepin, and State of Minnesota, have invented a new and useful Improvement in Furnaces; and we do hereby declare that the following is a full, clear, and exact description thereof, which will enable others skilled in the art to make and use the same, reference being had to the accompanying drawings, forming a part of this specification.

This invention relates a new and improved method of constructing furnaces for heating dwelling-houses and public buildings by heated air, and the invention consists in the novel arrangement of fire-box, heating-drums, and radiating-tubes and flues, as will be hereinafter described.

Figure 1 represents a front elevation of the furnace, showing the fire-box and smoke-passages.

Figure 2 is a side elevation, shewing one of the smoke-drums broken away, so as to expose the interior, giving a side view, also, of the fire-box and the smoke-pipes.

Figure 3 is a top view, showing the position of the vertical air-tubes through the fire-drum A.

Similar letters of reference indicate corresponding parts.

A represents the fire-drum or furnace proper, it being a vertical cylinder, with vertical air-tubes passing through it, as seen in fig. 3.

B is the furnace-door.

C represents annular elliptical-shaped drums, through which the smoke and product of combustion pass.

D D represent pipe-flues, which connect the furnace proper or drum A with the drums C.

E E represent pipes or flues, which connect the back ends of the drums C with chimney F.

G represents a damper in the chimney F.

J is the smoke-flue from chimney F.

H represents partitions in each of the drums C, which serve to retard the currents of smoke and heated gases as they pass through the drums.

a represents the vertical air-tubes, which pass through the furnace-drum A.

The air enters from below into the spaces within the annular drums C, and passes from them upward through the vertical air-tubes a in part and in contact with the heated surface of the furnace-drum A.

By opening the damper G, the heat and products of combustion may pass directly into the chimney, and out through the flue J.

By closing the damper G, the heat in the furnace will be compelled to pass between the air-tubes a, and to enter the fuel-tubes D D, by which it is conducted into the drums C. In passing through these drums it is retarded in its course by the partition-plates H, but finally enters the tubes or flues E, by which it is conducted into the chimney F and flue J, above the damper G.

The damper may be adjusted so as to suit the required temperature or the state of the atmosphere.

The rod of the damper extends forward to the front of the furnace, and is marked f.

In front there are apertures in the drums C, for cleaning the same, to which suitable doors are adjusted.

In this example of our invention, the furnace is arranged for wood as fuel, but we do not confine ourselves to any particular kind of fuel, nor to any particular proportions or materials in the construction of the furnace.

It is designed to place the furnace in a chamber of suitable size and construction, from which the heated air may be distributed, as may be desired.

Having thus described our invention, what we claim as new, and desire to secure by Letters Patent, is—

1. The arrangement and combination of the furnace-drum A, (with the vertical air-tubes a,) the annular flue-drums C, the smoke-flues D and E, and the chimney-flues F and J, substantially as described for the purposes set forth.

2. The partition-plates H and damper G, in combination with the furnace-drum A, annular flue-drums C, smoke-flues D E, and chimney-flues F J, as herein shown and described.

The above specification of our invention signed by us, this   day of   , 1867.

WM. H. LEE,
CHAS. M. HARDENBERGH.
